UNITED STATES PATENT OFFICE

EDWARD SEPELER, OF BERLIN-NEWCOLOGNE, GERMANY

PROPELLER

Application filed April 5, 1929, Serial No. 352,676, and in Germany December 5, 1925.

My invention relates to propellers which may be designed to transmit or absorb power and may operate in gaseous and liquid media. It is an object of my invention to provide means for regulating the position of the propeller blades in conformity with the thrust, the weight or the velocity of the driving or driven medium, with the power delivered or absorbed, or with other factors.

10 To this end I provide means for applying absorbed, or with other factors.
to the propeller blades centrifugal, spring and residual medium forces, such as air forces in a propeller for aerial craft.

15 It has already been proposed to adjust the blades of a propeller by a force resulting from the opposite action of centrifugal and thrust forces, the blades being moved backwards or forwards in conformity with the variations of the thrust and their movement being utilized for turning the blades by means of links or cam faces.

28 It has also been proposed to arrange the blades for axial displacement with respect to the propeller shaft, to transmit to a compression spring a reaction of the centrifugal forces exerted by the blades upon their axial displacement and to translate such axial displacement of the blades into turning movement of the blades about their axes by means
29 of cam faces.

In the drawings affixed to this specification and forming part thereof two types of propellers embodying my invention are illustrated diagrammatically by way of example.

35 In the drawings
 Fig. 1 is a plan view of the first type,
 Fig. 2 is a section on the line 2—2 in Fig. 1,
 Fig. 3 is a section on the line 3—3 in Fig. 2,
 Fig. 4 is an end elevation of the second
 40 type, and

Fig. 5 is a section on the line V—V in Fig. 4.

Referring to the drawings, 3 is the propeller shaft, 4 is a boss at the end of the shaft, 1 and 2 are propeller blades, each with a stem 13, such stem being supported for rotation about the common axis of its blade in suitable bearings 18', for instance ball bearings, in the boss 4, and 5 and 6 are balance weights at the end of the stem 13 of each blade, respectively, which are arranged ec-

centrically with respect to the axis of the corresponding blade, as can best be seen in the weight 5 in Fig. 4, the balance weights being provided for the purpose of placing the centre of gravity of each blade into a plane coincident with the axis about which the propeller is rotating.

7 is a through-bore in the boss 4 which is arranged at right angles to the stems 13, or substantially so. 8 and 9 are balance weights which are fitted to slide in either end of the bore 7 in radial direction with respect to the axis of the propeller shaft 3; 11 and 12 are pulleys or sectors on the stems 13 of the propeller blades, 10 is a spring housed in an axial extension 4' of the boss 4, and 14 and 15 are cables which are secured to the spring 10 at one end, to one of the weights 8, 9 at the other end, and supported intermediate their ends on the pulleys or sectors 11, 12, or attached to such pulleys. It will appear that the points where the cables 14 and 15 are connected with the spring 10 are in the extension of tangents to the pulleys 11 and 12. The contraction of the spring 10 is limited by flanges at the ends of the weights 8, 9.

When the propeller rotates about its shaft 3, a torque resulting from centrifugal action is generated in all parts which are arranged eccentrically with respect to the axis about which each blade is adapted to turn, this torque turning each blade about its stem 13 until the torque is balanced by the reaction of the spring 10. By means of the cables 14, 15 the forces resulting from deformation of the spring 10, variations in the position of the blades, residual medium (air) forces and all inertia forces tending to turn the blades are positively interrelated, even if the several factors are not equal to each other. If

the amount, for which the blades require adjusting is small, the weights 8, 9 may be dispensed with and only the centrifugal action of the weights turning with the blades, the eccentric weights 5, 6, and/or the pulleys 11, 12 may be relied on for adjusting the blades, and if the amount is smaller still, the cables 14, 15 may be displaced by links (not shown) connecting the blade stems 13 with the spring 10.

Instead of a single cable for each blade, two or a plurality of parallel cables may be provided and attached to diametrically opposite points on the perimeter of the spring.

- 5 In this case the cables do not extend in the axial plane of the system and therefore the propeller shaft 3 may be extended into the boss and through the spring 10 as far as the end of the axial extension 4', as shown in
10 Fig. 4, with a nut 33 at its outer end.

An example for this arrangement of cables is shown in Fig. 4, in which, however, the spring 10 is secured on the outside of the extension 4'. Instead of a single pulley 11 or 12 at the centre of each stem 13, as shown in Fig. 3, pulleys 11', 11'' and 12', 12'' are arranged on the stem at either side of the boss 4. Each pulley supports a cable 14 or 15 and these cables are attached to the spring 10 by shackles 14' and 14'', Fig. 5, so that the reaction of the spring is transmitted to each blade by a cable at either side of the extension 4'. The contraction of the spring 10 is limited by checks 16 which are engaged by
25 shoulders on the pulleys, the shoulders 34 and 35 of the pulleys 11' and 12', respectively, being visible in Fig. 4. It will be understood that in this type the shaft 3 may extend as far as the end of the extension 4'.

- 30 I have illustrated a type of propeller in which eccentric weights 5, 6 on the blade stems 13 are combined with weights 8, 9, which can be displaced in radial direction, as shown in Figs. 1, 2 and 3, and in Fig. 4 I have illustrated a propeller in which the centrifugal weights 8, 9 are dispensed with and only the eccentric weights 5 and 6 are provided, but I wish it to be understood that in the modification illustrated in Fig. 4 I may provide
35 the centrifugal weights 8, 9 in combination with the eccentric weights 5, 6, and that in the type illustrated in Figs. 1 to 3, I may dispense with the eccentric weights 5, 6 or with the centrifugal weights 8, 9, as required, without departing from my invention.

The faces of the blades may be so positioned with respect to the axis, about which each blade is adjusted, that the thrust forces are either absorbed altogether by the bearings
50 13' of the blade stems 13 or are utilized for assisting the spring 10 or the inertia forces in the form of a residual torque, for the purpose of influencing the regulating characteristic.

- 55 The operation of the new device is very efficient and reliable and absolutely uniform speed of revolution has been obtained, independently of the load, in a wind tunnel at air velocities of 20 to 50 metres per second.

60 In some of the claims, a "lever arm" is referred to. It is understood that this term was selected for the radial arm at which the forces act on the stems 13, for instance at the perimeter of the pulleys or sectors 11, 12.

65 I wish it to be understood that I do not

desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. A propeller comprising a shaft, two blades adapted to rotate bodily with said propeller and to turn about their own axes, a spring on said propeller arranged coaxially to said shaft and connected with said two blades so as to expose itself to their turning about their respective axes and rotary means operatively connecting said spring to said blades which rotary means are so designed that said spring acts uniformly on both blades.

2. A propeller comprising a shaft, two blades adapted to rotate bodily with said propeller and to turn about their own axes, a spring on said propeller arranged coaxially to said shaft and connected with said two blades so as to oppose itself to their turning about their respective axes, and a weight arranged to be subjected to centrifugal action when said propeller is rotating, and so positioned with respect to said spring as to counteract the action exerted by said spring on said blades.

3. A propeller comprising a shaft, two blades adapted to rotate bodily with said propeller and to turn about their own axes, a spring on said propeller arranged coaxially to said shaft and connected with said two blades so as to oppose itself to their turning about their respective axes, and a balance weight on each blade which is so arranged as to place the centre of gravity of said blades into a plane coincident with the axis, about which said propeller is rotating.

4. A propeller comprising a shaft, two blades adapted to rotate bodily with said propeller and to turn about their own axes, a spring on said propeller arranged coaxially to said shaft and connected with said two blades so as to oppose itself to their turning about their respective axes, and a balance weight on each blade arranged eccentrically with respect to the axis of said blade so as to place the centre of gravity of said blades into a plane coincident with the axis, about which said propeller is rotating.

5. A propeller comprising a shaft, a boss on said shaft, two blades arranged in said boss so as to be capable of turning about their axes, a spring on said boss arranged coaxially to said shaft and means for deforming said spring in dependency from the rotation of said blades.

6. A propeller comprising a shaft, a boss on said shaft, two blade stems in said boss, a lever arm on each stem, a spring on said boss arranged coaxially to said shaft and connected to said arm, a centrifugal weight also connected to said arm in such manner that its centrifugal action will counteract the pressure of said spring and an eccentric weight on said stem.

10 7. A propeller comprising a shaft, a boss on said shaft, blade stems in said boss, lever arms spaced axially on each stem and a spring on said boss arranged coaxially to said shaft and connected to said arms.

15 8. A propeller comprising a shaft, a boss on said shaft, blade stems in said boss, a pulley on each blade stem, and a spring on said boss connected to said pulley.

9. A propeller comprising a shaft, a boss on said shaft, blade stems in said boss, pulleys on each blade stem on either side of said boss, a spring on said boss, and cables connecting said spring and said pulleys.

In testimony whereof I affix my signature.
